UNITED STATES PATENT OFFICE.

CHARLES E. GEORGE, OF BOSTON, MASSACHUSETTS.

MOUTHPIECE FOR MUSICAL INSTRUMENTS.

1,178,513.

Specification of Letters Patent. Patented Apr. 11, 1916.

Application filed December 1, 1913. Serial No. 803,916.

To all whom it may concern:

Be it known that I, CHARLES E. GEORGE, of Boston, in the county of Suffolk and State of Massachusetts, have invented certain new and useful Improvements in Mouthpieces for Musical Instruments, of which the following is a specification.

This invention relates to an improvement in mouth-pieces for cornets, trumpets, and similar musical instruments. In many instances it is necessary or desirable for musicians who play cornets and trumpets to change quite frequently from one to the other. For instance, during an entertainment or other occasion it is necessary to play a cornet for a portion of the time and then to play a trumpet; then again when playing in an orchestra in a theater one quality of tone is desired, while in a café the other tone is desired. For a player to change from one instrument to the other frequently, or even from one form of entertainment to the other, and render satisfactory music is very difficult, with instruments having mouth-pieces as ordinarily constructed. This is due to several causes. First, it is almost impossible to shape the rims of different mouth-pieces identically the same in every respect, so that they will have identically the same feeling to the lips of the player. Second, the cup portion of the mouth-piece for a cornet is somewhat deeper than that for a trumpet, and the pressure of the air in these cups is somewhat different. This, taken in connection with the different feeling to the lips, renders it very trying for the player to change from one to the other frequently.

Accordingly, the primary object of the invention is to provide a set of parts whereby the player may play a cornet or a trumpet with the same rim for the mouth-piece. That is, for one size of bore for the stem, a set will ordinarily comprise one rim, one cornet cup, one cornet stem, one trumpet cup, and one trumpet stem.

It is the purpose of this invention to provide several stems having various sizes of bore, which may be used with either cup, thus enabling the player to obtain any desired effect or different qualities of tone.

The invention will be readily understood from an inspection of the drawing, in which—

Figure 1 is a side elevation of a trumpet mouth-piece embodying the invention, Fig.

2 is a plan view of the mouth-piece, Fig. 3 is a central longitudinal section through the trumpet mouth-piece, and Fig. 4 is a similar view of a cornet mouth-piece. 60

As illustrated in Fig. 3, the trumpet mouth-piece comprises a tubular stem 10, a cup 11, and a rim 12. The stem 10 is provided at one end with a reduced externally threaded neck 14, which is adapted to fit a corresponding internally threaded recess 16 in the lower end of the cup 11. The stem 10 is provided for a portion of its length with a cylindrical bore 18, which then merges into a tapering bore 19 flaring toward the lower end of the stem. The diameter of the bore 18 corresponds to the diameter of the hole 20 in the bottom of the cup, as shown in Fig. 3. If the stems having smaller bores are used, the upper end of the bore 18 is flared slightly 75 so that the sides of the hole 20 in the bottom of the cup merge into the bore 18, whereby a smooth surface free from shoulders is provided in the cup and stem. 70

The cup 11 is externally screw-threaded 80 at its upper end to fit the corresponding internally threaded rim 12. This rim may be shaped as desired to suit the player. This rim and cup may be screwed upon a stem having any desired bore, all of said stems 85 having their upper ends screw-threaded to fit the recess 16 in the bottom of the cup, and having the upper ends of their bores shaped to merge into the opening 20 in the bottom of the cup. Frequently a player desires to 90 have several stems, each with a different size of bore 18, in order to have a variety of effects, but the rim is always the same, and consequently the feeling to the lips is always 95 the same, thus giving confidence to the player and obviating the necessity of considerable recurrent practice with each mouth-piece before again becoming accustomed to it, as is the case with mouth-pieces as ordinarily constructed. 100

As illustrated in Fig. 4 the cornet mouth-piece comprises a stem 24, which is somewhat shorter than a trumpet stem, but otherwise its construction will be the same as the stem 10 described above. The stem 24 is 105 provided at its upper end with an externally threaded neck 26, which is interchangeable with the neck 14 on the stem 10, and fits a corresponding internally threaded recess 28 in the lower end of the cup 30. The cup 30 is similar to the cup 11, but is slightly 110 deeper, and it is externally threaded at its

upper end to fit the rim 12, it being understood that only one rim is provided for the two cups. The hole 32 in the bottom of the cup 30 is of the same size as the hole 20 in the bottom of the cup 11, and the cylindrical bore 34 corresponds to the bore 18 of the tube or stem 10. Thus with the construction above set forth it will be observed that if a musician is desirous of playing a cornet 10 after having played a trumpet, it is merely necessary to remove the rim 12 from the trumpet mouth-piece and screw it upon the cornet mouth-piece. The feeling of the mouth-piece to the lips is therefore the same, 15 the slight differences in pressure and tone quality of the two instruments being practically negligible and causing no appreciable annoyance or hesitancy.

A trumpet cup and rim may be used on 20 a cornet, if the player happens to have only the one cup with him, that is, the trumpet cup can be screwed onto the cornet stem or shank, the only effect being a slightly less full and perfect cornet tone, since the trumpet cup when used on a cornet will render 25 a tone having the quality of a trumpet slightly, but not sufficiently to be objectionable. It is not so easy, however, to play a trumpet with a cornet mouth-piece and obtain as good results from the trumpet.

Although I have shown and described the invention as particularly adapted for use 30 with a cornet and a trumpet, it is to be understood that it is not limited to such use, 35 but may be applied to a baritone, trombone, and other socalled "brass" instruments. A single rim is adapted for use with several different cups, and these cups in turn can be fitted to several different tubes or stems having 40 various qualities, thus giving a wide

range for the player, it being understood that the stems detachably fit the leader pipe to their respective instruments.

What I claim is:

1. A mouth piece of the character described comprising an inner section, the latter including a tubular stem externally threaded contiguous to its upper end, an intermediate section having its upper end externally threaded and its lower end counterbored and internally threaded for engagement with the threaded portion of said stem, and an outer section counterbored and internally threaded to engage the externally threaded upper portion of the intermediate section, the bore of each section forming a continuation of the preceding section. 45

2. A mouth-piece comprising an inner section including a tubular stem and a bell-shaped head thereon, the outer end of said head being reduced and externally threaded, an intermediate section counterbored and threaded internally for engagement with the threaded portion of said head, said intermediate section being also reduced and externally threaded at its outer end, and an outer section counterbored and threaded internally at its inner end for engagement with the externally threaded portion of the intermediate section, the bores of said sections forming continuations of one another 60 to provide a complete bore for said mouth-piece. 65

In testimony whereof I have affixed my signature in the presence of two witnesses. 70

CHARLES E. GEORGE.
